UNITED STATES PATENT OFFICE.

WILLIAM HAAS, OF NEW YORK, N. Y.

CREATING DRAFT IN CHIMNEYS.

SPECIFICATION forming part of Letters Patent No. 375,995, dated January 3, 1888.

Application filed July 27, 1887. Serial No. 245,450. (No model.)

To all whom it may concern:

Be it known that I, WILLIAM HAAS, of the city, county, and State of New York, have invented certain new and useful Improvements 5 in Creating Drafts in Chimneys by Means of Exhaust-Steam, of which the following is a specification.

This invention has for its object to furnish improved means for creating draft in chimneys by exhaust steam, said means being specially applicable for the chimneys of boiler-furnaces, so as to increase the draft of said furnaces; and the invention consists of the herein-described device for creating draft in 15 chimneys by means of exhaust-steam, which comprises an exhaust-steam pipe or pipes terminating below the end of the chimney, and an inclosing-chimney-cap provided above the chimney with a conical trough and a discharge- 20 pipe for the water of condensation, as will appear more fully hereinafter, and finally be pointed out in the claims.

In the accompanying drawings, Figure 1 represents a side elevation of a chimney with 25 my improved means for increasing the draft of the same; and Fig. 2 is a horizontal section on line *xx*, Fig. 1.

Similar letters of reference indicate corresponding parts.

In the drawings, A represents the end of the chimney, which is preferably formed of a tube of glazed earthenware or suitable vitrified material that is capable of resisting the corrosion produced theron by the condensation of 30 steam. The exhaust-steam is conducted from the engine by an exhaust-pipe, B, to the chimney, said pipe terminating in one or two discharge-pipes, *b b*, below the discharge opening of the chimney-tube A. The chimney-tube A 35 and the exhaust-pipes *b b* are inclosed by a chimney-cap, C, of sufficient size, which is made of suitable sheet metal, and provided above the chimney-cap A with a conical trough, *d*, that serves to collect the water of condensation and discharge the same through a nozzle, *d'*, to the outside. A second annular collector, *e*, of inverted conical shape, is arranged above the conical trough *d*, and is made of less width than said trough, so as to shed the water of 45 condensation into the same. The exhaust-steam discharged through the pipes *b b* into the cylindrical chimney-cap C creates a par-

tial vacuum above the mouth of the chimney-tube A, and creates thereby a suction in the same, so that the smoke and gases of combustion in the chimney are drawn with increased velocity in upward direction and discharged through the chimney-tube A. The water of condensation from the exhaust-steam is collected in the trough and discharged to the outside of the chimney-cap C by a discharge-nozzle, *d'*. In this manner faulty chimneys which have not sufficient draft to keep the fire in the boiler-furnaces sufficiently bright can be effectively improved and the increased draft 60 required for the boiler-furnace produced in a cheap and effective manner. If it be desired to produce a still greater draft, live steam may be used, which is, however, more expensive than the use of exhaust-steam supplied by the 65 engine.

I am aware that the introduction of a jet of steam in the smoke-stack or chimney of a boiler-furnace for increasing the draft of the same is well known, and I do not claim this 75 feature, broadly, but desire to limit myself to the special means shown for accomplishing the object.

Having thus described my invention, I claim as new and desire to secure by Letters Patent— 80

1. The combination, with a chimney-tube, of a steam pipe or pipes terminating outside of the same, a chimney-cap inclosing the chimney and steam-pipes, a conical trough located above the mouths of the chimney and steam- 85 pipes, and a discharge-nozzle for the water of condensation.

2. The combination, with a chimney-tube, of a steam pipe or pipes terminating outside of the same, a chimney cap inclosing the chimney and steam-pipes, a conical-trough located above the mouths of the chimney and steam-pipes, an inverted conical collector above the trough, and a discharge-nozzle for the water of condensation from the trough, substantially as 90 set forth.

In testimony that I claim the foregoing as my invention I have signed my name in presence of two subscribing witnesses.

WILLIAM HAAS.
